UNITED STATES PATENT OFFICE.

JOHN H. HANLON, OF SOMERVILLE, MASSACHUSETTS.

TRACK-SANDER.

No. 906,224.

Specification of Letters Patent.

Patented Dec. 8, 1908.

Application filed April 4, 1907. Serial No. 366,286.

To all whom it may concern:

Be it known that I, JOHN H. HANLON, citizen of the United States, residing at Somerville, in the county of Middlesex and State 5 of Massachusetts, have invented a certain new and useful Improvement in Track-Sanders, of which the following is a specification, reference being had therein to the accompanying drawings.

10 My invention has for its object to produce a track sander of the kind sometimes known as an outside sander which shall not be subject to the difficulties heretofore arising in the employment of these sanders.

15 Outside sanders are adapted to be removed from the sand box from the outside, so that they may be cleaned without removing the sand from the box, as has heretofore been necessary with most inside sanders, so far 20 as is now known to me. My improved outside sander may be readily applied to almost any sand box, it only being required to drill a single hole in the wall or casing of the box.

In my improved sander, the air discharge 25 nozzle is provided with means for collecting any scale, dirt or oil in a trap, thus preventing it from reaching the air discharge nozzle, and the nozzle may be readily removed and cleaned if it becomes clogged. If any 30 small obstructions like pebbles accumulate in the sander or at the entrance of the sand discharge pipe, they may also be readily removed. All cleaning operations may be performed without removing the sand from the 35 box.

The invention will be fully understood from the following description taken in connection with the accompanying drawings, and the novel features thereof are pointed 40 out and clearly defined in the claims at the close of the specification.

Referring to the drawings,—Figure 1 is a plan view of a sander embodying my invention. Fig. 2 is a vertical section on line 45 2—2, Fig. 1. Fig. 3 is a vertical section similar to that in Fig. 2, but with the cover and air discharge nozzle removed.

In the drawings,—There is indicated at 11 the wall of the sand box in which a hole is 50 drilled and tapped to receive the sander body 12. This hole is made very low down on the sand box, so that practically all the sand in the box may be used before it is necessary to refill it. The sander body 12 is screw threaded, as shown at 13 for engagement with the hole in the wall 11, and the

said sander body 12 projects inwardly into the interior of the said box for any convenient distance, preferably, however, for a distance such that the sand will not run out by 60 gravity. If, for instance, the sand lies at an angle of 45 degrees, the horizontal portion 14 of the interior of the sander body will be of a length equal to or greater than the diameter of the said interior projecting portion 14. 65 The sand discharge pipe 15 is connected to the said body 12 on the lower side of the said body at a convenient angle and a cleanout opening provided with a plug 16 is located directly above it. The said cleanout 70 plug extends only a short distance into the opening 17 in the body 12 in which it is received, so as to permit sand to collect in the said opening 17 and form a cushion or buffer which effectually prevents undue wear 75 of the parts opposite the air discharge nozzle.

On the upper side of the sander body 12, there is an opening 40 which is closed by a cover 18 held in place by the bolts 19 and 20 (see Fig. 1). Attached to this cover or 80 preferably cast integral with it is the air inlet 21 attached to the outer end of which is the air pipe 22. The said air inlet 21 terminates at its inner end in a trap 23 closed by a screw plug 24, the said trap 23 being 85 slightly below the level of the air discharge aperture. Any bits of scale or oil, or flakes of grease or dust such as are likely to be introduced into the air pipe 22 from the air pump or other source of air supply, are deposited in this trap, and are not likely to 90 find their way into the air discharge aperture.

The air inlet 21 is formed with a recess 25 through the wall of which is drilled the air 95 discharge aperture or nozzle 26, through which the air is discharged from the air pipe 22 into the interior of the sander casing 12. Within the said air aperture 26, I preferably locate a vibrator 27 provided with a 100 looped end carried on a cross wire 28. This vibrator is caused by the discharge of the compressed air through the air passage, to move rapidly or flutter, and tends to prevent any foreign substances from lodging in the 105 air discharge aperture and also to loosen any obstructions which have lodged there. The said air discharge aperture 26 is located directly opposite the sand cushion formed in the opening 17, so that a minimum 110 wear of the parts is produced.

The interior of the sander casing 12 is

provided with a small, upwardly projecting ¹¹⁰ 29, the top of which is below the air aperture 26, and serves to prevent any sand from being carried by the force of gravity ¹⁵ down the sand discharge pipe 15 when the engine is thrown out of its level position on curves of high elevation. The sand is drawn into the body of the sander through the open interior end of the sander, and also ¹⁰ through a hole or slot 41 (see Fig. 3) cut in the bottom of the interior end of the sander just back of the point where the sander body engages the wall of the box. This hole takes the sand from the bottom of ¹⁵ the box, and makes it possible for the sander to use nearly all the sand in the box.

If, for any reason, the air discharge aperture becomes clogged, through the presence ²⁰ of foreign substances in the air inlet pipe, it may be quickly and easily cleaned by unscrewing the air pipe 22 and removing the cover 18, after which the air inlet may be withdrawn and the foreign substances taken out and the air nozzle cleaned by the removal of the plug 24 at the back of the trap ²⁵ 23. In case the interior of the sander body becomes clogged by the presence of pebbles, roots or fibrous material in the sand, it may usually be cleaned by removing the plug 16 ³⁰ 30 after the cover 18 and attached inlet 21 have been removed or if the foreign substances cannot be removed by this means, the sand discharge pipe 15 may be disconnected and the sander body unscrewed from the box. ³⁵ This arrangement of parts enables the user of the sander to keep it in perfect working order for the discharge of the required amount of sand to the wheels of the locomotive for a very large percentage of the time, and the time lost by cleaning the sander and the danger resulting from the sander being out of ⁴⁰ operative condition are both reduced to a minimum.

What I claim is:

- 45 1. In a track sander and in combination with a sander body, an air inlet pipe, an air nozzle and a trap in the said air pipe to receive and collect foreign substances therein.
2. In a track sander and in combination ⁵⁰ with a sand box and a sand discharge pipe, a sander body having an opening exterior to the sand box, an air inlet pipe extending through the said opening to a portion of the sander body which is within the sand box ⁵⁵ having an air discharge opening facing away from the sand box and a trap at its inner end to receive and collect foreign substances in the air pipe.
3. In a track sander and in combination ⁶⁰ with a sand box and a sand discharge pipe, a sander body having an opening exterior to the sand box, an air inlet pipe extending through the said opening to a portion of the

sander body which is within the sand box having an opening at its extreme inner end ⁶⁵ and a plug closing the said opening and forming a trap to receive and collect foreign substances in the air pipe, and having an air discharge aperture opposite the said trap and facing away from the sand box. ⁷⁰

4. In a track sander and in combination with a sand box and a sand discharge pipe, a sander body mainly exterior to the sand box and having an opening in said exterior portion, a cover for said opening and an air ⁷⁵ inlet pipe passing through said cover to enter the interior of the sander body.

5. In a track sander and in combination with a sand box and a sand discharge pipe, a sander body having an opening exterior to the sand box, a cover for said opening, and an air inlet pipe integral with the said cover extending to a portion of the sander body which is within the said sand box and provided with an air discharge aperture facing ⁸⁵ the said sand discharge pipe.

6. In a track sander, the combination with a sand box and a sand discharge pipe of a sander body mainly exterior to the sand box, but having its inner end opening into the sand box and having a cleanout opening on its upper side exterior to the sand box, an air inlet entering the sander body through said cleanout opening on the upper side of the sander body, and having an air ⁹⁵ discharge aperture facing the said sand discharge pipe.

7. In a track sander, the combination with a sand box and a sand discharge pipe, of a sander body mainly exterior to the sand ¹⁰⁰ box, but having its inner end opening into the sand box and having an opening on its upper side exterior to the sand box, said sander body also being provided with a sand cushion, an air inlet entering the sander body through the said opening on the upper side of the sander body at an angle with the horizontal, and having a horizontal air discharge aperture facing the said sand cushion.

8. In a track sander, the combination with a sand box and a sand discharge pipe, of a sander body mainly exterior to the sand box, but having an open inner end extending into the sand box, an air discharge nozzle within the said sander body, and a rib with ¹¹⁰ in the said sander body and disposed transversely thereof in front of and below the air discharge nozzle to prevent the discharge of sand by gravity into the sand discharge pipe. ¹¹⁵

In testimony whereof I affix my signature, in presence of two witnesses.

JOHN H. HANLON.
